UNITED STATES PATENT OFFICE.

FRED A. DOLPH, OF CHICAGO, ILLINOIS.

TYPE-WRITING MACHINE.

1,232,246.

Specification of Letters Patent.

Patented July 3, 1917.

Application filed September 25, 1916. Serial No. 122,012.

To all whom it may concern:

Be it known that I, FRED A. DOLPH, a citizen of the United States of America, and a resident of Chicago, county of Cook, and 5 State of Illinois, have invented certain new and useful Improvements in Type-Writing Machines, of which the following is a specification.

This invention relates to typewriting machines of that general class which is designed with particular reference to requirements of court reporting and similar work.

Among the purposes of the invention is to decrease the time required for operating 10 such machines by employing certain mechanisms, movements of which may be accomplished at comparatively high speed, and to provide improved constructions including means whereby keys may be successively 15 or simultaneously depressed as rapidly as desired, separate means under the control of said keys being arranged for effecting an impression of an entire line after the required number of keys have been depressed.

20 Further objects of the invention are to provide improved means whereby the different keys of the keyboard may be differentially depressed to control the setting of type carriers in such manner that each key 25 may be employed for setting a plurality of different characters; to provide an improved adjustable automatic line spacing mechanism; and to provide means for automatically throwing out of operation the paper 30 feed or line spacing mechanism when the paper is manually adjusted backwardly.

An illustrative embodiment of this invention is shown in the accompanying drawings, in which:

40 Figure 1 is a plan view of a type writer constructed according to this invention.

Fig. 2 is a view in elevation of a longitudinal section of the machine.

Fig. 3 is a transverse vertical section taken 45 on the line B—B of Fig. 2.

Fig. 4 is a front view partly in section of the platen and related mechanism.

Fig. 5 is a sectional view in elevation on the line A—A of Fig. 4.

50 Fig. 6 shows details of the means employed for throwing out of operation the paper feed device.

Fig. 7 is an enlarged detail of one of the typewriter keys and its mounting.

Fig. 8 is a sectional view taken on the 55 line C—C of Fig. 7.

Fig. 9 is a detail showing means for differentially adjusting key detents.

Fig. 10 is a detail of one of the type carriers.

60 Figs. 11 and 12 show details of means for releasing keys upon completions of operations of the machine.

It is well known that such typewriting machines wherein the keys individually effect the impression of the desired characters in succession cannot be efficiently operated at the required speed for some classes of work, for the reason that it is impossible to effect the impression of combinations of 70 letters, as required for printing syllables or words, by a single stroke. Various mechanisms have been proposed in this art and in linotype or matrix-making machines, for accomplishing somewhat similar purposes to 75 that of the present invention, but frequently employing more or less complicated mechanism and means under the control of the keys for setting type bars at the time of depression of the keys.

80 In the present machine, the keys are set upon their depression, and after the required number have been depressed for controlling the setting of a line of type, a movable device is operated to effect the setting 85 of the type carriers as controlled by the keys and to operate the impression and paper feed mechanisms.

85 In its general arrangement, the present machine is provided with a keyboard comprising a plurality of duplicated banks with keys extending from the front to the rear of the keyboard. The number of keys in each bank preferably corresponds to the 90 number of letters in the alphabet, and the 95 keys are similarly arranged in each bank. Thus, the "A" keys form the lowermost rows of keys from side to side of the machine, and the "B" keys the second row from the bottom, etc. A key détent is provided for each bank of keys for retaining in set position a depressed key. The key détents are differentially adjustable by separate manipulative devices in order that different retaining shoulders thereon may 100 be positioned to coöperate with pins on the keys, so that the keys may be depressed different distances and retained in different 105

positions in order that each may differentially control the type carrier for its respective bank.

The type carriers are in the form of bars, 5 one being provided for each bank of keys, and are loosely supported in channels cut in the reciprocating type carriage which has a motion in the direction of length of the key banks. Thus, after keys are depressed 10 for controlling the setting of a line of type, the carriage is reciprocated, causing all the type bars to be moved forwardly until the same are stopped by engagement with the depressed keys. Toward the end of the forward stroke of the carriage, inking rollers 15 pass over the type and then the platen is automatically rocked downwardly, effecting the impression of a line on the paper supported thereon. During the return motion 20 of the platen, when the type bed or carriage moves rearwardly, the paper is fed to a position for receiving an impression of the next line. As the platen arrives at its initial position, all of the key detents are 25 pushed rearwardly slightly, and return releasing the depressed keys.

Referring to the drawings, the frame 1 is shown arranged for supporting the keyboard unit 2 and a reciprocating type carriage 3. A platen frame 4 is pivoted by 30 means of pins 5 to lugs 6 on frame 1, and may be rocked downwardly against the action of springs 7 to effect an impression from type bars 8 through the opening 9 in frame 1.

The machine may be motor driven, but as here shown power for operating the machine, including the adjustment of the type and rocking of the platen, is effected by 40 means of crank arms 10 connected together by operating handle 10.1 and pivoted to frame 1 by a shaft 10.2. Secured to the outer end of the cranks are straps 11 extending from the frame to wheels 12 on the shaft 13 journaled in frame 1. The straps 11 are also secured to wheels 12, and rigid with the latter on shaft 13 are wheels 14 to which are secured at one end straps 15 in turn riveted at points 16 to the upper 50 end of the type bed 3. Straps 15 from thence pass over rollers 17 on the frame 1 and at their free ends carry counter weights 18. By this arrangement, when crank 10 is pulled forwardly, the wheels 12 and 14 are 55 rotated to the right, (Fig. 2) and through the straps 15 pulling the type bed or carriage 3 forwardly and downwardly its full stroke as guided in frame 1. When the crank handle is released, the carriage 3 re- 60 turns to its initial position as shown in Fig. 2 by weights 18.

The type bars 8 at their forward ends are bent into fan formation to extend outwardly so that the ends of said bars are respectively 65 in alinement with their corresponding banks

of keys 19 (Fig. 3). The parts 20 of the bars which are in alinement with the different banks of keys are bent upwardly as shown in Fig. 3 and are slidable in slots 21 in the keyboard frame 22. These bent 70 portions of the type bars at their extreme upper ends have a plurality of shoulders 23 for engagement with depressed keys upon the forward stroke of carriage 3. The lower ends 24 of the shanks of the keys are suitably 75 formed to act as stops for the type bars by engagement with the desired ones of shoulders 23. As shown by dotted lines in Fig. 8, each key may be depressed to three different 80 positions in order that it may stop the type bar for such bank at three different points. 85

The carriage 3 supports inking rollers 25 which receive ink from the inking surfaces 26 and 26.1 of frame 1 and ink the type through the opening 9 during the reciprocation of the carriage. This carriage also supports rollers 27 in position to engage the edges 28 of platen frame 4 after the type have been inked, causing the platen 29 to rock downwardly and effect the impression 90 through opening 9. Upon the return of the carriage 3, the springs 7 restore the platen to normal position.

The platen 29, as shown in detail in Figs. 4 and 5, may be of usual construction, and 95 is provided with a ratchet wheel 30 for engagement with a pawl 31 in order that the platen may be rotated as required for line spacing.

The paper feed mechanism comprises 100 means for controlling pawl 31 with respect to ratchet 30 during the oscillating motion of the platen, and when it is moved toward and away from the type carriers. Pawl 31 is pivoted to the upper end of an arm 32, 105 in turn pivoted on the platen shaft 33. The lower end of arm 32 is slotted to receive the pin 34 on an adjustable block 35 carried on the end of a lever 36. This lever may be adjusted to different positions, thereby shifting the pin 34 along slot 32. Lever 36 may be retained in its adjusted positions by a spring 37 thereon engaging a toothed member 38 fixed to frame 1. Since the pivotal support for the platen is out of axial alinement with the pin 34, the rocking motion of platen frame 4 results in causing the arm 32 to rock around its pivotal support 33 and thereby cause the pawl 31 to oscillate back and forth with respect to ratchet 30, and 110 rotating the platen as required for line spacing. The platen shaft 33 supports the usual knurled head 39 by which it may be rotated in either direction. In order that pawl 31 may be disengaged from ratchet 30 upon 115 rotation in one direction of the knurled head 39, this head is secured to a sleeve 40 loose on the shaft 33 but carrying rigid a disk 41 having tangential slots 42 for engagement with pins 43 on radially adjustable sectors 120 125

44. These sectors are suitably located to engage a pin 45 on pawl 31 and disengage the pawl on the initial motion of the knurled head 39 prior to its rotating the platen. The 5 knurled head transmits its motion to the platen through the pins 43 and sectors 44 which are grooved and slideable along pins 46 on a disk 47 fast to platen shaft 33.

The frame 50 of the keyboard as shown in 10 Fig. 3 is provided with slots 21 into which extend the shoulder portions 23 of the type bars. The upper ends of slots 21 are enlarged to provide space for the adjustable key detents 52 and the key pins 53 which coöperate with said detents. The slots 51 are preferably drilled out at the location of the keys and the pins 53, to properly guide and prevent displacement of the keys. Each key is 15 depressible against the action of a spring 54 encircling the upper end of the shank of the key and bearing between the head 55 thereof and a shoulder 56 on the frame 50. Each key detent 52 is provided with a shou- 20 dered portion 57 at the location of each key on the corresponding bank. These shoulders coöperate with pins 53 for the purpose of retaining keys in their depressed position. Normally, the upper shoulder is 25 in position to be engaged by the pin on the corresponding key, but the detent 52 is adjustable so that one of the three shoulders on the part 57 thereof may be positioned to coöperate with the key pin. According to 30 the adjustment of the detent 52, a key may, be retained in different depressed positions, 35 so that the lower end of the shank 24 is in alinement with any one of the shoulders on the portions 23 of the type bars. By this means, each key may stop the corresponding 40 type bar at three different positions, and in this manner effect the setting of three different type, such as a capital or small letter, or some special character. When a key is 45 depressed, the pin 53 of such key engages one of the shoulders on the detent, camming the same upwardly until the pin clears the shoulder when the detent drops by gravity, retaining the key in its depressed position.

50 The means for adjusting the detents 52 so that the different shoulders 58 thereof are brought into operative relationship with the keys, comprise the pivoted manipulative members 59. One of these members is pro- 55 vided for each bank of keys, and the lower ends thereof are in position to engage pins 65 on the corresponding key detents. A slight forward motion of member 59 serves 60 to push the detent rearwardly so that the second row of shoulders 58 thereof is positioned opposite pins 53. A further forward motion of the member 59 will cause the lower row of shoulders 58 to be positioned in line with the key pins. Each detent is 65 retained in its adjusted position by shoul-

der pawls 60 which are spring pressed into engagement with teeth 61 and 61.1 on the member 59.

The member 59 is depressible against the action of a spring 62 by means of either keys 63 or 64 integral therewith. When either of these keys is depressed, the member 59 engages a pin 65 on the corresponding key detent, shifting the same upwardly so that one of the two lower rows of shoulders 58 thereof is positioned to coöperate with the key pins 53. When the key 63 is depressed as far as the surface plate of the keyboard, the pawl 60 engages the shoulders 61, whereas when the key 64 is depressed, the pawl 60 engages the shoulder 61.1. In this manner, the detents are differentially adjustable to regulate the stroke of the typewriter keys 19. Each key detent is provided with a pin 66 in line with the shoulder 67 of pawl 60, so that by a further upward shifting of the detents, the pawl 60 may be disengaged from the members 59, permitting the latter to return to normal position. For the purpose of so disengaging the pawl 60 and likewise releasing depressed keys, each detent is provided with a recess 68 at its upper end, as shown in Fig. 8. A rod 69 passes through the recesses 68 and is carried by a pair of depending arms 70 rigid on a transverse shaft 71 journaled in the key frames. This shaft also carries rigidly thereon a member 72 which may be manually rocked forward thereby causing the rod 69 to lift all of the detents and release the keys, 100 and also through such action to permit the members 59 to return to normal position, in case the latter members had been previously adjusted away from normal position. The detents may be individually operated to release depressed keys by levers 73 pivoted on the shaft 71 and having their lower arms 74 extending into the recess 68 of the corresponding detent. Accordingly, by rocking any one of the arms 73 forwardly, its 105 respective detent may be shifted upwardly and release a depressed key in such bank.

For the purpose of releasing all the keys at the end of an operation of the machine, one of the operating levers 10, as shown in 115 Figs. 11 and 12, is provided with a pin 75 in position to engage an arm 76 on the shaft 71, causing this arm to rock the shaft on the return stroke of lever 10. In order that the arm 76 may idly ride over pin 75 during the forward stroke of operating lever 10, this arm is loosely journaled on the shaft 71, but is provided with a split hub 77 through which extends a pin 78 fast to the shaft 71. Thus, the arm 76 may rock idly 120 during the forward motion of lever 10, but become effective in rocking the shaft 71 during the return stroke of the lever and thereby release all keys at the end of an 125 operation of the machine.

In operating the machine, assuming that the mechanism is in its normal position as shown in Fig. 2, the operator may depress the required keys to control the setting of type for an entire line by successively depressing the keys or simultaneously depressing keys in any desired combinations, it being understood that to cause spaces to appear between words, the operator omits to 5 depress a key in the banks corresponding in location to such spaces. The keys may be depressed different distances in order that each may control the setting of a plurality of type, but the distance to which 10 a key may be depressed is determined by a preliminary setting of the detents 52. The setting of the detents is controlled by depressing members 59, which through engagement with the pin 65 may position the 15 detents upwardly different distances, the members 59 being temporarily retained in adjusted position by the pawl 60. After the keys representing one line have been depressed, the operator draws the handle 10.1 20 forwardly through the belt connections 11 and 15, causing the type carriage to be drawn downwardly and forwardly along its guides. The type bars are permitted to move with the carriage until the shoulders 25 23 thereof engage depressed keys. The type bars by this means are retained in adjusted position during the further forward motion of the carriage. The inking rollers are journaled in the type carriage, in position to 30 roll over and receive ink from the surfaces 26, in inking the adjusted type bars through the opening 9. After the type are inked, the rollers 27 engage the inclined edges 28 of the platen carrying frame, rocking this 35 40 frame downwardly against the action of spring 7, causing the platen 29 to make an impression on the paper thereon, of the line of type which are positioned for an impression through the opening 9. Upon the release of the operating handle 10.1, the 45 weights 18 serve to return the carriage to its normal position, permitting the platen frame to return to normal position under the action of its spring 7 and also through 50 the belt connections with the operating handle, restoring it to its normal position. As the pin 75 on lever 10 passes the arm 76 on the shaft 71, the latter is rocked rearwardly, causing the shaft 71 to rock the required distance to engage the rod 69 with 55 all of the detents, restoring them to normal position and permitting the release of depressed keys.

Although but one specific embodiment of 60 this invention has been herein shown and described, it will be understood that numerous details of the construction shown may be altered or omitted without departing from the spirit of this invention as defined 65 by the following claims.

I claim:—

1. A machine of the class described, comprising a plurality of banks of keys, the keys of each bank being arranged for differential adjustment, a type carrier for each 70 of said banks, and means for differentially adjusting said type carriers according to the keys depressed and also according to the differential adjustment of said keys.

2. In a machine of the class described, a 75 keyboard comprising a plurality of banks of depressible keys, type carriers under the control of said keys, and adjustable means for retaining keys in depressed position at different points along their stroke. 80

3. In a typewriting machine, the combination of a frame, a type-carriage mounted for reciprocation in said frame, type bars slidably mounted in said carriage, and a keyboard comprising a bank of keys for each 85 type bar, each of said keys being differentially adjustable for the purpose of differentially controlling its respective type bar.

4. In a typewriting machine, the combination of a frame, a type-carriage mounted for reciprocation in said frame, type bars slidably mounted in said carriage, a keyboard comprising a bank of keys for each type bar, each of said keys being differentially adjustable for the purpose of differentially controlling its respective type bar, a platen, a pivoted support for said platen, means for reciprocating said type-carriage, and connections for rocking said platen support for the purpose of engaging the platen with adjusted type bars. 90

5. In a typewriting machine, the combination of a frame, a type-carriage mounted for reciprocation in said frame, type bars 105 slidably mounted in said carriage, a keyboard comprising a bank of keys for each type bar, each of said keys being differentially adjustable for the purpose of differentially controlling its respective type bar, a platen, a pivoted support for said platen, and means for reciprocating said type-carriage, said carriage being provided with a member for engaging and rocking said platen support for the purpose of engaging 110 the platen with adjusted type bars.

6. In a typewriting machine, the combination of a frame, type bars mounted for reciprocation in said frame, means for reciprocating said type bars, and a keyboard 120 for controlling the extent of movement of said type bars, said keyboard comprising a bank of keys for each type bar, and each of said keys being differentially adjustable for the purpose of differentially controlling its 125 respective type bar.

7. In a typewriting machine, the combination of a frame, type carriers mounted for differential adjustment in said frame, means for driving said type carriers, and a 130

keyboard for controlling the extent of movement of said type carriers, said keyboard comprising a bank of keys for each type bar and each of said keys being differentially adjustable for the purpose of differentially controlling its respective type carrier.

Signed at Baltimore this 21st day of Sept., 1916.
